(57) **CLAIM**

The ornamental design for a doghouse, as shown and described.

DESCRIPTION

FIG. 1 is a front, right, and top perspective view of a doghouse, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 1; and,

FIG. 10 is a front, right, and top perspective view of the doghouse of FIG. 1 in one state.

The broken lines and the deemphasized surface in the FIGS. 2 and 8 illustrate portions of the doghouse that form no part of the claimed design. All other broken lines show the bounds of the enlarged portions that form no part of the claimed design.
